US0D1051426S

(12) **United States Design Patent** (10) **Patent No.:** **US D1,051,426 S**
(45) **Date of Patent:** **** Nov. 12, 2024**

(54) **WATER TANK FOR INDOOR PLANT CULTIVATOR**

(71) Applicant: **LG ELECTRONICS INC.**, Seoul (KR)

(72) Inventors: **Minsub Kim**, Seoul (KR); **Kyukwan Choi**, Seoul (KR); **Yong Kim**, Seoul (KR)

(73) Assignee: **LG ELECTRONICS INC.**, Seoul (KR)

(**) Term: **15 Years**

(21) Appl. No.: **29/819,159**

(22) Filed: **Dec. 13, 2021**

(51) LOC (14) Cl. **25-03**

(52) U.S. Cl.

USPC **D23/202**

(57) **CLAIM**

The ornamental design for a water tank for indoor plant cultivator as shown and described.

DESCRIPTION

FIG. 1 is a front perspective view of the water tank for indoor plant cultivator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of a portion of FIG. 1;

FIG. 9 is reference view showing the state of use that the lid has been closed; and,

FIG. 10 is a reference view showing the state of use that the claimed design is being installed at the inside bottom of indoor plant cultivator.

The portions of FIG. 10 drawn in broken lines show environmental structure only and form no part of the claimed design.

1 Claim, 10 Drawing Sheets
